DESIGN FOR A MOTOR DRIVEN ACTUATOR FOR MOVABLE PARTS OF AN AIRPLANE OR THE LIKE

Carl F. Hilgeman, Buffalo, N. Y., assignor to
Eastman Machine Company, Buffalo, N. Y.

Application April 11, 1945, Serial No. 118,947

Term of patent 14 years

(Cl. D71—1)

To all whom it may concern:

Be it known that I, Carl F. Hilgeman, a citizen of the United States, residing at Buffalo, Erie County, State of New York, have invented a new, original, and ornamental Design for a Motor Driven Actuator for Movable Parts of an Airplane or the like, of which the following is a specification, reference being had to the accompanying drawings, forming a part thereof.

In said drawings:

Fig. 1 is a side elevational view of a motor driven actuator for movable parts of an airplane or the like showing my design.

Fig. 2 is a plan view thereof.

Fig. 3 is an end elevational view thereof.

The dominant features of the design reside in the portions shown by solid lines in the drawings.

I claim:

The ornamental design for a motor driven actuator for movable parts of an airplane or the like, substantially as shown and described.

CARL F. HILGEMAN.
